UNITED STATES PATENT OFFICE.

GEORGE COLVIN KENNEDY, OF WATERLOO, IOWA.

SECTIONAL CRYPT.

1,330,192.

Specification of Letters Patent. Patented Feb. 10, 1920.

Application filed April 12, 1915, Serial No. 20,850. Renewed July 2, 1919. Serial No. 308,292.

To all whom it may concern:

Be it known that I, GEORGE COLVIN KENNEDY, a citizen of the United States of America, and a resident of Waterloo, Black-hawk county, Iowa, have invented certain new and useful Improvements in Sectional Crypts, of which the following is a specification.

My invention relates to improvements in mausoleum crypts, and the object of my improvement is to provide crypts assembled from detachably jointed sections into an association capable of receiving additions of like parts to form other associated crypts from time to time.

This object I have accomplished by the means which are hereinafter described and claimed, and which are illustrated in the accompanying drawings, in which:

Fig. 1 is a front elevation of two of the assembled crypts, one crypt showing the front closure removed.

Fig. 2 is a side elevation of one of the sectional side-plates of a crypt with the end closures attached thereto and in vertical section.

Fig. 3 is a detail perspective view of the underside of one of the horizontal division-plates, with part broken away.

Fig. 4 is an enlarged detail cross section of the joint connection between plates of said crypt.

Fig. 5 is a perspective detail view, fragmentary, in cross-section, of one of the interlocking parts of said joint-connection.

Fig. 6 is a similar fragmentary view of another of the interlocking parts of said joint connection.

Fig. 7 is a horizontal section of the vertical joint connection between two of the side plate sections.

Fig. 8 is a vertical section of one of the horizontal joint connections between the sections of one of the horizontal division plates.

Fig. 9 is a fragmentary detail of coacting parts of the side-plate joint connections, showing them slightly separated.

Fig. 10 is an enlarged detail cross section, in a modified form of joint connection, between the crypt plates.

Similar numerals of reference denote corresponding parts throughout the several views.

My improved crypt structure comprises a plurality of side-plates, associated with

horizontal division plates, which latter serve as top-plates and bottom plates respectively for crypts arranged in superposition, said plates being assembled together detachably by means of my improved joint connections about to be described. These plates are preferably made of cast-iron, but may be formed of other suitable materials.

The side-plates 1 are of rectangular form and may be made in single plates or sectional as desired. I have, however, shown the side-plates 1 as formed in two sections for convenience on account of the nature of the material and the handling thereof when formed of cast-iron. The sections of the side-plates may be secured together by means of any suitable tight joint connection. In Figs. 2 and 7, I have shown one kind of joint connection therefor. One of the side-plate parts has integral spaced forked extensions 24 adapted to receive the abutting vertical edge part of the adjacent section, said forked part 24 having orificed ears 25 which latter are secured to the underlying section by means of bolts 26 passed through said orifices and other aligned orifices in the section and fastened by nuts 27. A sealing layer 31 of cement or other impervious material is filled in the joint thus formed. The side-plates 1 have their upper longitudinal edges widened at 8, said widened part having a medial longitudinal groove 9 contracted upwardly between two tongues 12, and having on each side of said medial groove a longitudinal groove 10 widening upwardly between the tongues 12 and outer tongues 11.

The lower longitudinal edge of the plate 1 is formed of a medial downwardly directed longitudinal rib or tongue 13 widening downwardly flanked on either side by angular ribs 14. Two of said side-plates 1 can be interlocked in superposition in the same vertical plane by simply sliding a tongue 13 on the uppermost plate endwise within the medial longitudinal groove 9 in the under plate. In Fig. 6 is shown a troughed bar 8 formed like the widened part 8 of said plate, but adapted to serve as joint securing means for the lowermost side-plate of such a superposed series. In Fig. 5 is shown another bar ribbed like the lowermost part of said plate 1 and adapted to serve as an interlocking means for the final or topmost joint of such a series. It will be observed that in this form of connection,

the tongue 13 is locked within the groove 9 and that the side-ribs 14 are supported upon the tops of the like ribs 12 underneath, which locks said parts together immovably.

5 The numeral 2 denotes a horizontal division plate which may be a single plate or divided into sections, as indicated in Fig. 8, the joints 29 between the sections being arranged to alternate or break joint with 10 the joints 24 of the side-plates. The joint 29 is a transverse integral rib or shelf on the lower side of one section, and adapted to receive and support the abutting end-part of another section thereon, with a layer 15 of cement or other impervious substance between them to seal the joint. When the plates 1 and 2 are made of cast-iron, it is preferable for integral crossed ribs 3 and 5, and 4 and 7 to be formed thereon. The side 20 plates have such ribs on opposite sides, but the horizontal plates 2 need have them only on the lower side, since the latter plates carry less weight than the former. These ribs, as well as the cross-connections 24 and 25 29 lend a good deal of stiffness to the plate sections, and permit castings to be made which are capable of sustaining relatively heavy weights while saving in material.

Referring to said Fig. 9, the joints between 30 the sections of a side-plate 1 may be set off from the like joint of the side plate section underneath in order to properly seal said connections, and in this case said sections may differ somewhat in length.

35 Referring now to said Fig. 4, the horizontal plate 2 has on its opposite longitudinal edges a widened part provided with the three longitudinal ribs 16, 15 and 19. The middle rib 15 fits within the groove 10 of the side plate 1 with the rib 11 of the latter fitting within the groove 17 between said ribs 15 and 16. The other rib 19 fits over the upper surface 18 of the side rib 14 on the superposed plate 1. The rib 15 is widened outwardly so as to be interlocked between the ribs 12 and 17 on one plate and the rib 14 on the other plate. This forms a rigid interlocking connection between said plates and the whole forms an 40 45 50 intimately united joint connection for the crypts, immovable and capable of sustaining much weight and strain. The convoluted character of the joint parts also makes it very easy to seal the same hermetically and forms a rigid structure needing no bolts nor other form of fastenings.

55 In Fig. 10, I have shown a modified form of said joint in which the side grooves 10 also have restricted neck portions in order 60 to form interlocking seats for the outwardly widened ribs 15 on the plates 2 on either side of the plate 1. It will be observed that in the latter construction, the plate 2 is locked directly to the widened head 8 of 65 the under-side plate 1, whereas, in the

former construction, it is only interlocked between the interlocked parts of said superposed side-plates. The joint connection shown is such as to permit of an indefinite extension upward and sidewise of similar 70 crypts by the addition of similar plates connected thereto. On this account in a mausoleum, only as many crypts need be set up at any time as are required for immediate use, thus minimizing the investment. 75

Any kind of a suitable closure may be used to seal each end of such a crypt, but I have shown closures 22 having flanged parts 23 secured within the open ends of a crypt by means of bolts 20 and nuts 21. 80 The surfaces of all said metallic parts may be coated with a suitable anti-corrosive material to preserve them indefinitely from corrosion.

Various changes may be made in the 85 form, arrangement, and other features of said device, without departing from the scope of the principles of or the protection of this invention.

Having described my invention, what I 90 claim as new, and desire to secure by Letters Patent, is:

1. A crypt structure, comprising side plates, each having a longitudinal groove along one longitudinal widened edge, and each having a longitudinally directed tongue along its opposite longitudinal edge, the tongue adapted to form an interlocked sliding joint with the grooved longitudinal edge of a like side-plate located adjacent thereto in the same plane, the groove in its first mentioned edge adapted to form an interlocked sliding joint with the tongue on another like plate in the same plane, and each plate having grooved longitudinal integral ribs on each side of its said grooved widened longitudinal edge, and horizontal plates, each having ribbed longitudinal edges adapted to be secured in the said ribbed parts of the first-mentioned plates 100 105 110 by an interlocked sliding joint, to form a plurality of hollow crypts.

2. A crypt structure, comprising vertically aligned side-plates and horizontally aligned plates associated therewith, all said plates meeting at a common place of junction and detachably interlocked at that place, one longitudinal edge of each side-plate being widened, said widened part having a longitudinal medial inwardly widened groove, and having at each side thereon an inwardly narrowed groove, the abutting longitudinal edge of the aligned side-plate having a medial longitudinal outwardly widened rib adapted to be slidably introduced within 115 120 125 and interlocked with the said medial groove in the first-mentioned side-plate, and having at each side a longitudinal rib adapted to provide an inwardly widened groove in association with the inner wall of a side 130

groove in said first-mentioned plate, each horizontal plate having on each longitudinal edge an outwardly widened rib adapted to be slidably introduced within and interlocked with the adjacent side groove of the first-mentioned plate, to form an inclosed crypt having attaching-means at their meeting-places for additional like plates.

3. A crypt structure, comprising vertically alined side-plates, and horizontally alined plates associated therewith, all said plates meeting at a common place of junction and detachably interlocked at that place, one longitudinal edge of each side-plate being widened, said widened part having a longitudinal medial inwardly widened groove, and having at each side thereof an inwardly narrowed groove, the abutting longitudinal edge of the alined side-plate having a medial longitudinal outwardly widened rib adapted to be slidably introduced within and interlocked with the said medial groove in the first-mentioned side-plate, and having at each side a longitudinal rib adapted to provide an inwardly-widened groove in association with the inner wall of a side-groove in said first-mentioned plate, each horizontal plate having on each longitudinal edge an outwardly widened rib adapted to be slidably introduced within and interlocked with the adjacent side groove of the first-mentioned plate, said horizontal plate also having along each longitudinal edge a longitudinal rib adapted to fit over the outermost projection of the abutting widened part on the adjacent side plate, to form a rigid hollow structure.

4. The combination of plates arranged to meet at their longitudinal edges to form knockdown hollow bodies, and having at said meeting edges mating engaging-means, certain of the plates which are positioned in the same plane having their longitudinal edge-connections in the form of interlocked joints separable by longitudinal sliding on each other, and the mating engaging-means for the cross-plates being duplicated on opposite sides of the first-mentioned plates to

permit of addition of other cross-plates thereto to form other hollow bodies connected thereto.

5. The combination of plates arranged vertically and having mating engaging-means along their longitudinal edges for other engaging-means on abutting edges of other plates in the same plane, and cross-plates, the first-mentioned plates having lateral engaging-means on opposite sides to engage and interlock with the abutting longitudinal edges of said cross-plates, to form a series of hollow bodies, capable of extension in either direction by the addition of other like vertical and cross-plates to supply other like hollow bodies.

6. A sectional structure composed of vertical and horizontal plates, the vertical plates being provided with a groove along one edge thereof and having the adjacent edge of another vertical plate provided with a tongue whose shape corresponds to the shape of said groove, a second groove parallel with and adjacent the first-mentioned groove adapted to receive a corresponding tongue formed on one edge of a horizontal plate and a shoulder adjacent the tongue on the second vertical plate adapted to abut against a corresponding portion on the horizontal plate and lock the plates against transverse movement.

7. In an expansible mausoleum the several crypts of which are composed of removable wall, bottom and top plates, wall plates, each having along one edge a plurality of grooves and having the opposite edge formed to fit in one of the grooves of an adjacent wall plate, and bottom and top plates, each having along a side thereof a rib adapted to fit in and interlock with another of said grooves in an adjacent wall plate.

Signed at Waterloo, Iowa, this 10th day of April, 1915.

GEORGE COLVIN KENNEDY.
